413

xx-PL 413. Ebenezer Weeman Design for Metallic Gates

Patented 16. Sept. 1851.—

The above is the drawing of my design for "Metal Gates" referred to in my application of the 16th instant, patented at the Patent Office on the 16th of July, 1851. I set out to show why I have rights in and to my name, etc.

Ebenezer Weeman, of Charleston, Mass.

Letters patent No 413. Dated Sept 16. 1851.

The schedule referred to in these Letters Patent and making part of the same.

To all persons whom it may concern:

Be it known that I the undersigned Ebenezer Weeman of Charleston in the County of Middlesex & Commonwealth of Massachusetts, black smith, have invented & produced a new and original design as a pattern for casting gates in metal, which design or pattern has not been known or used by others before my invention & production thereof, of which the following is a full & exact description.

My design is intended for a gate for tombs and for burial lots in cemeteries and on account of the emblem introduced is peculiarly fit for such purposes; but it can be used for all other purposes or places where ornamented gates or doors are required. The figure is shown by the wood cut impression, stamped upon the opposite page & attested by me as a part of this specification.

Des. 445

2

This design may be used for a gate with the front only cast in relief, as shown in the wood cut or both sides of the gate may be cast in relief according to circumstances.

I do not claim the design for the posts or pillars in this gateway, but only the form of the gate suspended between the posts; and I claim the design for gates of this pattern of whatever size they may be made & of whatever metal they may be cast and for whatever purposes they may be used.

In testimony whereof I the said Ebenezer Freeman here-to subscribe my name in presence of the witnesses whose names are here-to subscribed on the eighteenth day of July, A. D. 1857.
